UNITED STATES PATENT OFFICE.

CHARLES HVASS, OF NEW YORK, N. Y., ASSIGNOR OF ONE-HALF TO LAZARUS KAHNER, OF SAME PLACE.

DESIGN FOR A HEAD-FORMER FOR CIGARS.

SPECIFICATION forming part of Design No. 22,463, dated May 23, 1893.

Application filed March 6, 1893. Serial No. 464,922. Term of patent 14 years.

To all whom it may concern:

Be it known that I, CHARLES HVASS, a citizen of the United States, residing at New York, in the county of New York and State of New York, have invented and produced a new and original Design for Head-Formers for Cigars, of which the following is a specification.

The essential feature of my design consists in the shape, or configuration, of the surfaces 10 lying adjacent to the head rest and coinciding therewith.

In the drawings Figure 1 is a perspective view; Fig. 2 a plan view; Fig. 3 a front elevation; Fig. 4 an end elevation, and Fig. 5 a 15 rear elevation.

The head former comprises a block of irregular outline in plan, and substantially rectangular in front and end elevations. The block 1 has an extension 2, the ends of which 20 are rounded, and a substantially rectangular lug 3. Traversing the block and lying between the extension 2 and lug 3 is a conoidal aperture or head rest 4, above which lies an inverted V shaped slot 5. The surface 6 of the block inclines from the rear downwardly 25 to the aperture 4. The ledge 7 is lower than the ledge 8, both ledges defining the inverted V shaped slot. The surface 9 of the lug 3 is slightly convex, and rolls downward from the front to the rear, inclining toward the apex 30 of the inverted V shaped opening, as at 10, Fig. 4. In Fig. 5 the rear 11 of the lug 3 is a little higher than that part of the extension 2 which meets it at this point, and the lug rises gradually upward to the front of the 35 block.

Having described my design, I claim—

A design for a head former for cigars, substantially as herein shown and described.

Signed at the city, county, and State of New 40 York this 28th of January, 1893.

CHARLES HVASS.
